The drawing consists of three views of a mechanical assembly. The top view shows a main frame with a slot (13) containing a roller (10) and a lever (13). A curved plate (7) is attached to the frame. A large wheel (25) is mounted on a shaft, with a smaller wheel (26) attached to it. A curved plate (121) is also shown. The middle view shows a similar assembly with a different perspective of the frame and wheels. The bottom view shows a side view of the mechanism, including a wheel (21), a lever (23), and a motor (26) connected to a shaft. Various parts are labeled with numbers such as 13, 10, 14, 21, 23, 24, 25, 26, 7, 121, 122, 123, 124, 91, 240, 222, 223, and 224.

MACHINE FOR BUNDLING STACKS OF RINGS

Henry Gora, Bridgeport, Conn., assignor to Jenkins Bros., New York, N. Y., a corporation of New Jersey

Application March 27, 1933, Serial No. 663,042

24 Claims. (Cl. 100—31)

The invention relates to improvements in machines for bundling or clipping stacks of superposed articles, such as rings, by wrapping or bending strip binding material about the stacks, the machine including a magazine feed for segregating the articles into stacks containing a predetermined number and delivering the stacks to a holder, means for feeding the strip binding material to position for application to the stacks and coordinated means for clamping the stacks in the holder and for bending the strip binding material about the clamped stacks, as fully shown in the accompanying drawings, in which:—

Fig. 1 is a side elevation of the machine.

Fig. 2 is a front elevation.

Fig. 3 is a plan view.

Fig. 4 is an enlarged section on line 4—4 of Fig. 3.

Fig. 4a is an enlarged section on line 4a—4a of Fig. 3.

Fig. 5 is a partial plan and horizontal section of the conveyer and the strip applying means.

Fig. 6 is an elevation, partly in section, of the mechanism shown in Fig. 5.

Fig. 7 is a fragmentary side elevation showing the conveyer and one of the clip applying slides.

Figs. 8, 9 and 10 are detail views of a slide, with one-half removed, showing successive positions of the bending or clipping means.

Fig. 11 is an enlarged plan view of one of the subsidiary slides.

Fig. 12 is an elevation thereof.

Fig. 13 is a fragmentary sectional detail of the strip feed and crimping device.

Fig. 14 is a section on line 14—14 of Fig. 13.

Figs. 15 and 16 are perspective views of the knives.

Fig. 17 is a section on line 17—17 of Fig. 12.

Fig. 18 is a section on line 18—18 of Fig. 12.

Fig. 19 is an enlarged plan view of the magazine, stack former and feeder in its association with the conveyer.

Fig. 20 is a section on line 20—20 of Fig. 19.

Fig. 21 is an elevational detail of the rock lever.

Fig. 22 is a section on line 22—22 of Fig. 20.

Fig. 23 is a section on line 23—23 of Fig. 20.

Fig. 24 is a fragmentary sectional elevation of the magazine.

Fig. 25 is a fragmentary elevation of the magazine.

Fig. 26 is an elevation of one of the elements of the stack former.

Fig. 27 is a detail of one of the stack forming fingers.

Fig. 28 is a plan view of a clipped or bundled stack of rings.

Fig. 29 is a side elevation thereof.

As exemplified in the accompanying drawings, the machine is designed to segregate and feed stacks of jar rings, each stack containing twelve rings, to an intermittently moving conveyer made up of receptacles to hold a unit stack and present the stacks successively to means for feeding the strip binding material thereto, means for severing the binding material into predetermined lengths, means for clamping each stack in its receptacle, so that the stacks will be of substantially uniform thickness, and means for folding or bending the binding strip about the stacks, so that the latter will be delivered from the machine as unit bundles to facilitate distribution to ultimate users or purchasers.

Referring to the drawings, 1 indicates the frame of the machine, which may be conveniently constructed of angle bars, the top of the frame being provided with two parallel longitudinal stringers 2, 2 connected at intervals by cross pieces which carry the longitudinal rails 3, 3, which serve as guides for the conveyer mechanism.

Journalized in bearings 9 secured to the tops of the stringers 2, 2 is a shaft 8 to which are keyed sprocket wheels 7, 7, which serve to drive the conveyer 10, and secured to the forward ends of the stringers 2, 2 are bearings 6, 6 to which is secured a stationary shaft 5, upon which are mounted spaced disks 4, 4 about the peripheral edges of which the conveyer 10 is guided. The conveyer or carrier 10 comprises a series of links 11 each having parallel tongues 12 on its ends adapted to intermesh with coordinate tongues on the adjacent links, the intermeshing tongues being provided with registering openings which are engaged by pintles 13 on the ends of which are journaled rollers 14 which engage the tracks 3, sprocket wheels 7, 7 and guide disks 4, 4, respectively. Any slackness in the endless conveyer may be taken up by adjusting the bearings 6, 6.

Each of the links of the endless conveyer is fashioned to constitute a receptacle or holder for a stack of superposed rings, each stack containing twelve rings, and to present each stack in proper relation to means for clamping the stack in position in its receptacle, reducing it to substantially uniform thickness and to other mechanism which will be effective in bending or clipping lengths of strip binding material about the stack to form

the same into a unitary bundle capable of being freely handled. As indicated, there is formed in the body portion of each link a generally annular recess 15, somewhat larger than the rings 5 to be bundled, which recess is defined by a central core 16, the sides of the link and the core being provided with diametrically opposite generally rectangular recesses 17, which constitute openings through which the strip binding material may be 10 passed freely during the clipping operation, as will be hereinafter explained.

Stack forming mechanism

The machine is designed to operate upon stacks 15 of superposed rings, each stack preferably containing twelve rings and, in order to automatically supply stacks of the requisite number to each of the ring receptacles of the conveyer, the machine is provided with a novel form of magazine 20 and stack forming device, which is illustrated in detail in Figs. 19 to 27, inclusive. The magazine comprises a skeletonized generally cylindrical casing 44 adapted to receive a relatively large number of rings, said casing being mounted in 25 axial alignment with a cylindrical member 42, which is formed as an integral part of a yoke-like casting 41, which is pivoted to brackets 40 mounted on one of the cross bars of the machine, so that the lower end of the cylindrical casing 42 will be 30 in vertical alignment with the annular recess in each link of the conveyer chain, as the latter is intermittently halted in the operation of the machine. In order to accurately adjust and level the magazine, set screws 41' carried by brackets 35 40' are adapted to engage the lower face of the casting 41. It will be noted that the entire magazine may be swung to the left, as shown in Fig. 1, to permit the clearing of any rings that may jam in the machine during the operation thereof. Under ordinary service conditions, however, the magazine will be maintained in vertical relation, so that the rings stored therein will feed downward by gravity.

Secured to the lower part of the magazine section 44 by lugs 46 and bolts 47 is a ring 45, from which is suspended the means for segregating the stacks of rings and delivering the stacks successively to the receptacles in the links of the conveyer chain. This stack forming mechanism includes an upper ring member 49 provided with recesses 50 in its lower face, an intermediate ring 51 and a lower ring 59, which is provided with recesses 60 in its upper face, which, in other respects, is a duplicate of ring 49. These ring 55 members are secured together and to the ring 45 carried by the lower end of the magazine 44 by bolts 48. The intermediate ring 51 is provided with two sets of four pins 52 and 62, respectively, the pins 52 projecting from the upper surface 60 thereof and the pins 62 projecting from the lower surface of said ring. Pivoted to each of the pins 52 for swinging movement within the recesses 50 are separator fingers 53, which are generally shaped like a bell crank, each having a slotted or cleived outer end 55 and a thin blade-like portion 54 on its inner face, each of the blade-like members being adapted to operate in one of four vertical slots 43 formed in the tubular section 42 of the magazine. Similar but reversely disposed 65 separator fingers 63 are mounted on the pins 62 for pivotal movement within the slotted portions 60 of the lower ring 59, each of said elements 63 being provided with a slotted outer end 65 and knife-like inner end 64, which are also adapted 70 to be moved into and out of registry with the slots 75

43 in the member 42. The intermediate ring 51 is of less external diameter than the upper and lower rings 49 and 59 and disposed in the annular space formed by the assembled rings is an outer ring 70, which is provided with four pins 71 on its upper face engaging the slotted or cleived ends of the separator fingers 53 and four pins 72 projecting from its lower face engaging the corresponding slotted ends 65 of the separator fingers 63, so that, when the ring 70 is oscillated, one set 10 of separator fingers will be moved to project the knife-like ends thereof through the slots 43 in the lower part of the magazine into the path of movement of the rings in the magazine, while the other set of separator fingers will be retracted; 15 therefore, for each complete oscillation of the outer ring 70, a stack of twelve rings will be segregated from the rings in the upper part of the magazine by the upper set of separator fingers 53, while the previously separated stack of twelve 20 rings will be released by the lower set of separator fingers 63 and dropped into the registering receptacle in the conveyer chain, as indicated in Fig. 20. The necessary oscillatory motion of the outer ring 70 is effected by means of a rock lever 25 pivoted to a yoke 76, which is secured to one end of the casting 41, said rock lever comprising an arm 86 connected to a hub 85 by studs 87 and locked in position by a screw 88, engaging a threaded socket in a stud 77 secured to the bracket 30 76, and an arm 78 secured to the hub 85 and provided at its lower end with a longitudinal bore engaged by pin 80 secured to a clevis 79, which engages pins 82 carried by a pintle 81 secured in the periphery of the ring 70. The arm 86 has mounted on its outer end a roller 89 adapted to be engaged in a groove in one of the cams which operates the clipping mechanism to be hereinafter explained. Ring 51 is anchored to member 42 of the magazine by a set screw 75, which is applied to or removed from its locking relation through an enlarged opening 74 in ring 70, as shown in Figs. 22 and 25.

Conveyer drive

The movement of the conveyer is intermittent to permit each link to be arrested with the receptacle therein in alignment with the discharge end of the magazine to permit the stack of rings to be delivered from the latter into said receptacle. 50 The intermittent movement of the conveyer is effected by the following mechanism: An electric motor 20, mounted on the frame, is connected by shaft 20' with a set of reducing gears of any appropriate type, mounted in casing 21, which 55 reducing gears are adapted to be connected by a clutch to a sprocket wheel 23, which is connected by a sprocket chain 24 with a sprocket wheel 25 on shaft 26 journaled in bearings 103 mounted on the stringers 2, 2. Fast to the shaft 26 is the driving disk or plate 27 forming part of a Geneva gear, said disk having mounted on its face a pin and roller 28, which is adapted to impart partial rotations to the cooperating Geneva gear member 30 by successively engaging the radial slots 60 65 therein in the manner and form characteristic of this type of gear. Also connected to the plate 27 is a segmental boss 29, which serves to lock the member 30 against rotation, after the pin 28 has passed out of engagement with any slot in 70 the member 30. Said member 30 is secured to shaft 8 upon which the sprocket wheels 7 driving the conveyer 10 are secured, as hereinbefore explained. The Geneva gear, as described, is effective to move the conveyer a distance equal 75

to the length of one of the conveyer links and then to arrest the movement of the conveyer until the pin 28 on the driving plate or disk 27 engages the next succeeding slot in the member 5 30. The operation of the Geneva gear brings each link in the conveyer into alignment with the lower end of the magazine 44 to receive a stack of rings and advances the preceding link containing a stack of rings to the next position of rest, 10 where the stack is operated upon by certain means for clamping the stack and other means for clipping strip binding material about the stack to form the latter into a unitary bundle, as will be hereinafter explained.

15 *Binder strip feeding means*

In the preferred form of the machine, the strip material, comprising a flexible metal band or ribbon which is capable of being readily bent and 20 will retain the form to which it is bent, is supplied to the machine in the form of rolls or coils carried by reels or spools 111 disposed on opposite sides of the machine frame and carried by stub shafts 110, the hub of each spool being engaged 25 by a friction braking device 110', which may be adjusted to prevent the free rotation of the spools, but will admit of the latter turning upon the application of a pull to the strip material carried thereby. As shown in Figs. 1 and 2, each strip of 30 binding material 112 is led from its spool under a guide pulley 114 mounted on the lower part of the machine frame, thence over and under the rollers of a tensioning device 113, over a final guide roller 115 mounted on the inside of the machine frame, through an adjustable guide 150 35 secured to a housing 120, which is formed as an extension of a central table or cross plate 2' on the top of the machine frame. From the guide 150, the strip passes between feed rolls, thence 40 through a final guide 151 through an opening in the cross plate 2', to a position adjacent one of the lateral openings 17 in a link of the conveyer chain. There are two sets of feed rolls, one pair for each strip of binding material, and one set is 45 shown in detail in Fig. 13, and the mechanism for operating both sets is indicated in Fig. 6. Shafts 139 and 141, journaled in housing 120, carry rolls 143 and 142, respectively, shaft 141 being mounted in an adjustable bearing 141', 50 which is engaged by a spring 145 carried by set screw 144, by means of which the pressure exerted by the feed rolls on the binding strip may be regulated and which permits roll 142 to yield under abnormal pressure, such as would be exerted when one of the rolls is provided with indicia on its face to be embossed on the strip material as an identifying mark for the rings. The other pair of feed rolls is carried by shafts 135 55 and 137, the latter being journaled in an adjustable bearing 147 engaged by spring 149 carried by set screw 148, similar in all respects to the corresponding elements of the other pair of rolls.

Intermittent movement is imparted to the two sets of feed rolls to advance predetermined lengths 60 of the strip binder material between shearing knives and in position to be bent or folded about a stack of rings. A countershaft 91, journaled in bearings mounted on the stringers 2, 2, has secured thereto a second element 90 of a Geneva gear, similar to element 30 hereinbefore described, and which is intermittently actuated by the same driving disk or plate 27, the disposition and arrangement being such that, when element 30 is 65 being rotated by driving disk 27, element 90 is held in stationary or locked relation and vice

versa. Keyed to the shaft 91 is a bevel gear 124 meshing with a bevel pinion 123 on longitudinal shaft 121, which latter is journaled at one end in yoke 122 and near its other end in housing 120, this end of said shaft having keyed thereto gear 130 which is the first in a train of gears driving the two pairs of feed rolls, said gear 130 meshing with gear 131, which engages pinion 134 on shaft 135 of one feed roll, said pinion meshing with pinion 136 on shaft 137 of the cooperating feed roll. Gear 131 also drives gear 132, which drives pinion 138 on shaft 139 of feed roll 143, said pinion meshing with pinion 140 on shaft 141 of feed roll 142. The two pairs of feed rolls are thus actuated simultaneously to project equal lengths 15 of the binder strips into position to be severed and to be applied to opposite sides of the stacks of rings, the movement of the feed rolls being effected during a period of rest of the feed chain or conveyer, so that the ends of the binder strips will 20 be projected upwardly adjacent to and on opposite sides of a link of the conveyer chain, and in general parallelism with the lateral openings 17 in said link.

25 *Cutting and clipping mechanism*

Extending from cross plate 2' are two bracket-like members 160, slotted longitudinally at their outer ends and provided with dovetailed guides 161, which are engaged by cooperating grooves 30 formed in the bottoms of the slides which carry the clamping and clipping mechanism, said grooves being faced with wear plates 162 which are adjusted by set screws 163. Each slide comprises two castings 164 and 165 locked together 35 by cross bolts 166. The rear end of each slide is recessed, as indicated at Fig. 5, to permit the entrance of the periphery of an actuating cam 105. Mounted on a stud 168 on each of the slide members 164 is a roller 167 which engages a 40 groove 107 in one face of the corresponding disk 105, fashioned to advance and retract the cooperating slide with an intermittent dwell during substantially one-half revolution of the cam and to hold the slide stationary during the other half 45 rotation. The member 165 of each slide is provided with a slot 169, extending from its outer end, forming a guide for an auxiliary slide 170, which carries a roller 171 journaled on stud 172 and engaging a cam groove 106 on the opposite face of disk 105 to that in which groove 107 is located, said groove 106 conforming to groove 107, except in the intermediate dwell portion of the latter, which, as shown in Figs. 6, 9 and 10, is substituted 50 by a sharp reverse bend extending toward the periphery of the disk 105. This arrangement of the cam slots 106 and 107 in each disk 105 causes the main slide and the auxiliary slide to operate in unison, except during the dwell between the completion of the advance and the beginning of 55 the retraction of the main slide, when the auxiliary slide is advanced and retracted independently of the main slide by this sharply curved portion of the cam groove 106, which independent movement of the auxiliary slide is effected to actuate 60 the clipping means, which secures the binder strips about the stacks of rings.

Each auxiliary slide 170, as shown in detail in 65 Figs. 11, 12, 17 and 18, carries a rack bar 180 having teeth on its upper and lower edges, the function of which is to operate the clipping fingers, the movement of which fingers should be accurately regulated and adjusted, to which end the rack 180 is made adjustable longitudinally of the slide 170. The inner end of slide 170 is slotted to form guides 70 75

- for a block 175 to the face of which rack bar 180 is secured by screws 181, said block having two spaced perforated lugs 176 on its rear face engaged by an adjusting screw 178 having a collar 177 secured thereto between the lugs 176, the threaded end of the screw engaging a screw threaded boss 179 on slide 170 and being provided with a lock nut 179' to hold the set screw 178 and the rack bar 180 in any position of adjustment.
- 10 Mounted in the recessed inner walls of the slide sections 164 and 165 are two gear trains 190, 191 and 192 and 190', 191' and 192', gears 190 and 190' engaging the teeth on the opposite edges of rack bar 180 and the gears 192 and 192' engaging, respectively, mutilated gears 193 and 193', which are also journaled in the side walls of sections 164 and 165, said mutilated gears having angular fingers 194 and 194' formed thereon, adapted to engage the strip binding material and crimp or 20 bend the same about the stacks of rings, in the manner and form shown in Figs. 8, 9 and 10.

In order to reduce the stacks of rings to uniform thickness, while the binder strips are being applied, each of the main slides, constituted by the 25 half sections 164 and 165, is provided with two clamping dogs 200 pivoted on studs 201 mounted on the sides of the slide near the upper part of the forward edges thereof, each dog having substantially the form of a bell crank lever, one arm 30 of which carries an adjustable set screw 204 adapted to engage the side walls of a link of the conveyor chain, when the main slide is advanced toward the conveyer, and rock the dog into engagement with the top of the stack of rings carried by said link. Each dog is normally swung into inoperative position by a spring 202 having one end secured to the dog by a cross pin and the other end attached to the stud on which the dog is pivoted. The retractile movement of each dog is 40 limited by a stop pin thereon, which may be the pin by which the spring 202 is attached to the dog, said pin engaging the lower edge of a lug 195 projecting from the forward face of the main slide. These lugs 195 also constitute guides for the binding material, as the latter is fed to position for application, and are located in pairs at the top and 45 bottom of the front faces of each of the main slides.

Secured in recesses in the cross plate 2' are 50 fixed knives 196', one of which is shown in detail in Fig. 16, which cooperate with knives 196, one secured to the lower face of each main slide, each pair of knives cooperating to cut the section of strip binding material that has been fed to 55 position in the front face of each slide, as indicated in Figs. 8 and 10. The detail of knife 196 is shown in Fig. 15.

As hereinbefore stated, the rings are fed from the magazine 44 into the receptacles in the individual links of the conveyer chain, in stacks of twelve, by the automatic segregating and feeding means described, and the latter means is preferably actuated by one of the cam disks 105, which, as shown in Figs. 2 and 6, is provided on one face 65 with an additional cam groove 108 engaged by the roller 89 on the end of rock lever 86, said groove being formed to impart properly timed swinging movements to said rock lever, which effects alternate advance and retractile movements of the 70 sets of segregating fingers 54 and 64, as hereinbefore described.

The cam disks 105 are secured to the ends of shafts 102, journaled in brackets 103 and 104 mounted on the stringers 2, 2, each of said shafts 75 having on its other end a bevel gear 101, which

meshes with a similar bevel gear 100, the latter being secured to the respective ends of cross shaft 26, which is constantly driven during the operation of the machine.

Disposed longitudinally of the machine is an 5 endless belt conveyer 220 operating over pulleys 221, 222, which latter is driven by belt 223 from a pulley 224 mounted on a cross shaft 26. The conveyer belt 220 is designed to receive the bundles of rings, as the latter are discharged from 10 the conveyer 10, and to deliver the same into suitable receptacles or containers. In order to retain the bundled rings in the individual receptacles of the conveyer chain 10 until the links reach the position to discharge individual bundles 15 onto the conveyer belt 220, there is provided a spring finger 240 which is conveniently attached to bracket 122, the lower portion of said finger engaging the top surfaces of the links 11, as the latter pass successively around the sprocket wheels 20 7, thereby preventing the clipped or bundled stacks dropping out of the links prematurely.

As stated, the operation of the machine is controlled by a clutch adapted to connect and disconnect the sprocket wheel 23 with the shaft of the reducing gearing in casing 21, said clutch being operated by conventional linkage, such as 233 and 234, and foot pedal 230.

Operation

30

In the normal operation of the machine, the motor 20 drives the main shaft 26 continuously through reducing gearing in casing 21 and the chain and sprocket gearing 23, 24 and 25, and shaft 26 rotates driving disk 27 and Geneva gearing and the cam disks 105 in unison and at the same speed. Member 30 of the Geneva gear operates the conveyer 10 intermittently, advancing the latter by an amount equal to the length of one link of the conveyer during part of each rotation of the shaft 26 and driving disk 27, and holding the conveyer stationary during the remainder of each rotation of said shaft 26, thereby moving the links and chain successively under the discharge end of the magazine 44. As each link is 45 halted under the magazine, cam slot 108 in one of the cam disks 105 actuates rock lever 86, which moves ring 70 of the stack segregating unit to retract fingers 64 from under a stack of rings in the lower part of the magazine, permitting the 50 stack to drop into the annular receptacle 15 in the subjacent link of the conveyer, said ring 70 simultaneously projecting fingers 54 into the tier of rings in the magazine to support the tier of rings above the segregating unit. As the disk 55 105 continues its rotation, lever 86 is rocked in the opposite direction by the cam slot, thereby reversing the movement of ring 70, causing the latter to retract the upper set of fingers 54 of the stack segregating unit and project the lower set 60 of fingers 64 into the path of movement of the rings in the magazine. As the distance between the two sets of fingers 54 and 64, measured axially of the magazine, is equal to the height or thickness of a stack of rings to be bundled, each rotation of shaft 26 and cam disk 105 will effect the delivery of one stack, in the present instance twelve rings, to the receptacle in the link of the conveyer chain immediately blow the magazine. While one link of the conveyer chain 70 is receiving a stack of rings, the preceding link, which has already received a stack, is at rest between the slides which effects the compression and clipping of the stack, as shown in Figs. 5 and 6. After the conveyer chain 75

has been halted, member 90 of the Geneva gear is given a partial rotation by pin 28 on the driving disk 27, thereby operating the two pairs of feed rolls 142 and 143 through shaft 91, bevel gears 124, 123, shaft 121 and the train of gears in the housing 120, each pair of feed rolls feeding a length of strip binding material 112 upward through the guide 151 and opening in plate 2' into position opposite one of the lateral openings 17 in the proximate link and immediately adjacent the portion of the stack of rings exposed through said opening. Immediately following the feeding of the strip of binding material to position, the cam slots 106 and 107 in disks 105 move the main slides and the auxiliary slides carried thereby in unison toward the sides of the stationary link 11 containing the stack of rings to be clipped or bundled. As the operation of these coordinated main and auxiliary slides are the same, the operation of one of them will be particularly described. The roller 167 carried by the main slide engages the cam slot 107 in disk 105 and, when the roll passes out of the portion of the cam slot concentric with the axis of rotation of the cam, the main slide is moved forward until the front end thereof engages the side of link 11 of the conveyer chain and assumes the position shown in Fig. 6. Simultaneously, the roller 171 on the auxiliary slide 170 moves the auxiliary slide with the main slide, that is to say, the main and auxiliary slides are moved simultaneously to the same extent until they attain the position shown in Fig. 6. During the next partial rotation of cam disk 105, the main slide remains stationary, as the roller 167 engages the outer concentric portion of the cam groove 107. As the main slide approaches the end of its movement toward the conveyer, the set screws 204 carried by the clamping dogs 200 rock the latter on their pivots, causing the noses of the dogs to engage the top of the stack of rings carried by the link 11 and exercising sufficient pressure on the stack to force the rings therein into a compact body of uniform thickness or height, the dogs continuing this clamping action on the stack of rings until the bundling or clipping operation is completed. Just before the main slide reaches the end of its forward movement, the knife 196 carried thereby, in cooperation with the stationary knife 196', severs the portion of the binding strip projecting above the knives, said severed section being held in alignment between the two sets of lugs 195 and 195' on the forward face of the slide. As soon as the forward movement of the main slide ceases, the roller 171 on the auxiliary slide 170 passes into the sharply curved section of cam slot 106, thereby causing the auxiliary slide to move forward independently of the main slide, which forward movement causes the rack bar 180 to actuate the two trains of gearing journaled in the main slide, which effect a partial rotation of the clipping fingers 194 and 194', which latter engage the upper and lower portions of the severed section of the binding strip 112 and bend or fold the same over the top and bottom of the stack and thence down and up against the inner surface of the stack, in the manner and form particularly illustrated in Fig. 10, the completion of the clipping operation being effected when the roller 171 reaches the high point in the cam slot 106. Immediately thereafter, said roller passes into the descending portion of the slot 106, thereby retracting the auxiliary slide 170, together with rack bar 180, which reverses the movement of the gear

trains and swings the clipping fingers 194 and 194' backward into their retracted position. The further rotation of the cam disk 105 causes the rollers 167 and 171 to engage the declining portions of the cam slots 107 and 106, respectively, thereby causing both the main and auxiliary slides to move backward together until the rollers aforesaid engage the inner concentric portions of the respective cam slots, when the motion of both slides is arrested. Immediately after the retractile movement of the slides has been completed, the pin 28 on the driving disk 27 of the Geneva gear again engages element 30 of said gear to move the conveyer chain ahead the distance of another link and the series of operations hereinbefore described is repeated. The clipped or bundled stacks of rings are retained in the receptacles in the links until the links pass partially around the sprocket wheels 7 and each link reaches the ultimate point of discharge immediately above the conveyer belt 220, the spring finger 240 engaging the stack in the partially inverted link, as indicated in Fig. 4, to prevent the premature discharge of the bundled stack.

From the foregoing description, it is apparent that the strip binding material is drawn off of the reels in accurately predetermined lengths by the feed rollers and any kinks or deformations of the strip material is ironed out by the guide rollers and the stationary guides through which it is led, so that the proper length of smooth strip is ultimately presented to the clipping mechanism in position to be folded about the stack of superposed rings. If desired, the feed rolls may be provided with means for marking or impressing indicia in the strip binding material, the latter being of a character to take and retain the impressions, and, while capable of being readily bent or folded about a stack are of a consistency to retain the form into which they are so bent or folded, thereby insuring the stability and compactness of the clipped bundle of superposed rings, which latter may be handled and distributed without impairing their integrity, but nevertheless permitting the individual bundles to be broken down by passing a thin bladed instrument between the binding clips and the stack and bending back one end of each binding strip to free the rings.

What I claim is:

1. A machine for bundling stacks of superposed rings comprising a holder for a stack, means for feeding strip binding material parallel to the axis of a stack of rings to positions adjacent opposite sides of the stack, means for compressing the rings in a direction parallel to their axes, and means disposed on opposite sides of the stack for respectively bending the binding material around the ends of the stack while the latter is subjected to the compressing means.

2. A machine for bundling stacks of superposed rings, comprising a holder for a stack, means for feeding strip binding material to position adjacent the holder, and mechanism movable transversely of the axis of the stack involving means for severing a predetermined length of strip and means for bending the severed strip in opposite directions within the stack.

3. In a machine for bundling stacks of superposed rings, the combination with a conveyer having unit receptacles for the stacks, of means for feeding strip binding material parallel to the axis of a stack of rings to positions adjacent opposite sides of the stack, means for compressing the rings in a direction parallel to their axes,

means for severing predetermined lengths of the strip material, and means disposed on opposite sides of the stack for respectively bending the severed lengths of strip material about the stack 5 while the rings are compressed, each of said bending means including a pair of rigid finger-like members respectively adapted to bend a severed length of strip material across the ends of the stack and in opposite directions within the 10 stack.

4. In a machine for bundling stacks of superposed rings, the combination with a conveyer having unit receptacles for the stacks, of means for feeding strip binding material parallel to the axis of a stack of rings to a position adjacent the stack, a slide movable transversely of the axis of the stack, and mechanism mounted on said slide including means for compressing the rings in a direction parallel to their axes, means 15 for severing a predetermined length of binding material, and means for bending the severed length of binding material about the stack while the latter is subjected to the compressing means.

5. In a machine for bundling stacks of superposed rings, the combination with a conveyer having unit receptacles for the stacks, of means for feeding strip binding material parallel to the axis of a stack of rings to a position adjacent the stack, a slide movable transversely of the conveyer, and mechanism mounted on said slide including pivoted dogs movable into engagement with the receptacle containing the stack for compressing the rings in a direction parallel to their axes, means for severing a predetermined length of strip binding material, and means for bending the severed length of binding material about the stack while the latter is subjected to the compressing means.

6. In a machine for bundling stacks of superposed rings, the combination with a conveyer having unit receptacles for the stacks, of means for feeding strip binding material parallel to the axis of a stack of rings to a position adjacent the stack, a slide movable transversely of the conveyer, and mechanism mounted on said slide including pivoted dogs for compressing the rings in a direction parallel to their axes, means for severing a predetermined length of binding material, and pivoted finger-like members for bending the severed length of binding material about the stack while the latter is subjected to the compressing means.

7. A machine for bundling stacks of superposed rings, comprising an intermittently movable conveyer having receptacles for stacks of rings, means for feeding strip binding material parallel to the axis of a stack of rings to position adjacent the stack and mechanism movable edgewise of the stack involving coordinated means for clamping the stack and for bending the binding material about the stack while the latter is subjected to the clamping means.

8. A machine for bundling stacks of superposed rings, comprising an intermittently movable conveyer having receptacles for stacks of rings, means for feeding strip binding material to position adjacent the stack, coordinated means for clamping the stack, and mechanism movable edgewise of the stack involving means for severing a predetermined length of said strip and for bending said severed length about the stack while the latter is subjected to the clamping means.

9. A machine for bundling stacks of superposed rings, comprising a conveyer having re-

ceptacles for unit stacks of rings, means for feeding strip binding material parallel to the axis of a stack of rings to present said material in an upright position adjacent the stack, clamping means for pressing each stack in its receptacle when the latter reaches the position in which the stack is to be bundled, means movable transversely of the axis of the stack for bending the binding material about the stack while the latter is subjected to the clamping means, and timed gearing for intermittently operating the conveyer, the strip feeding means, the clamping means and the strip bending means.

10. A machine for bundling stacks of superposed rings, comprising a chain conveyer having links each provided with a recess to receive a unit stack and lateral openings extending into the body of the link, means for presenting strips of binding material to the stacks in alignment with the lateral openings in the links, transversely moving main slides having means for clamping the stacks in the receptacles and for bending the binding material about the stacks, auxiliary slides carried by the main slides and having means for actuating the strip bending means carried by the main slides, and timed driving gearing for intermittently operating the conveyer, the strip presenting means and the slides.

11. A machine as described in claim 10, in which the main slides are provided with means for severing the presented binding material into predetermined lengths.

12. A machine for bundling stacks of superposed rings, comprising a holder to receive a unit stack, means for feeding strip binding material to position adjacent the stack, a main slide movable toward and from the holder and having means for clamping the stack in the holder and for bending the binding material about the stack, an auxiliary slide on the main slide having means for actuating the bending means carried by the main slide, and timed gearing for operating the strip feeding means and the main and auxiliary slides.

13. A machine as described in claim 12, in which the clamping means comprises dogs pivoted on the main slide and moved into clamping position by engagement with the stack holder.

14. A machine as described in claim 12, in which the bending means comprises angular fingers pivoted to the main slide and having gear teeth, and means for actuating said fingers includes gears on the main slide and a rack bar on the auxiliary slide for driving said gears.

15. A machine for bundling stacks of superposed rings, comprising an intermittently moving conveyer having spaced receptacles for holding unit stacks, feed rolls for delivering strip binding material in position to be applied to a stack in one position of rest of the conveyer, main slides on opposite sides of the conveyer movable toward and from the latter, dogs on the slides actuated by engagement with the receptacles for clamping the stacks in the receptacles, bending fingers on said slides for clipping the binding material about said stacks, auxiliary slides on the main slides carrying means for operating said fingers on the main slides, and timed gearing actuating the conveyer, feed rolls and the main and auxiliary slides.

16. A machine as described in claim 15, in which the main slides are provided with knives for severing predetermined lengths of binding material after the latter has been delivered by the feed rolls.

17. A machine for bundling stacks of superposed rings involving means for feeding strip binding material in a substantially vertical direction to present said material in an upright position adjacent a side of a stack in parallelism to the axis of the stack, and means movable transversely of the axis of the stack for bending said material about the top and bottom of the stack and downwardly and upwardly within the stack.
18. A machine for bundling stacks of superposed rings involving means for feeding strip binding material in a substantially vertical direction to present said material in an upright position adjacent a side of a stack in parallelism to the axis of the stack, means for severing a predetermined length of said material while the latter is in an upright position, and means involving pivotally mounted members for bending said material around the ends of the stack and in opposite directions within the stack.
19. A machine for bundling stacks of superposed articles involving means for feeding strip binding material to a position adjacent a stack, means for severing a predetermined length of said strip material, and pivoted members respectively adapted to bend intermediate portions of the severed strip across the ends of the stack and to bend the respective end portions of the severed strip downwardly and upwardly along a side of the stack, each of said pivoted members having rigidly connected angularly disposed arms one of which is adapted to extend over the adjacent end of the stack in engagement with the severed strip and the other of which is adapted to overlap said side of the stack in engagement with the strip.
20. A machine for bundling stacks of superposed rings involving means for feeding strip binding material in a substantially vertical direction to present said material in an upright position adjacent a side of a stack, means for severing a predetermined length of said strip material, and pivoted members respectively adapted to bend intermediate portions of the severed strip across the ends of the stack and to bend the respective end portions of the strip down-

wardly and upwardly within the stack of rings, each of said pivoted members having rigidly connected angularly disposed arms one of which is adapted to extend across the adjacent end of the stack in engagement with the severed strip and the other of which is adapted to extend within the stack in engagement with said strip.

21. A machine for bundling stacks of superposed articles involving means for feeding strip binding material to a position adjacent the stack, movable means for compressing the stack engageable with the top thereof, and mechanism movable edgewise of the stack for actuating said compressing means, said mechanism having means for bending said strip material about the stack while the latter is subjected to the compressing means.

22. A machine for bundling stacks of superposed articles involving means for feeding strip binding material to a position adjacent a stack, and a slidable member movable edgewise of the stack, said member having movable means for clamping the stack engageable with the top thereof and also having means for bending the strip material about the stack while the latter is subjected to the clamping means.

23. A machine for bundling stacks of superposed articles involving means for feeding strip binding material to a position adjacent a stack, a slidable member movable edgewise of the stack having means for bending said material about the stack, and means for clamping the stack during operation of said bending means, said clamping means being engageable with the stack on opposite sides of said bending means.

24. A machine for bundling stacks of superposed articles involving means for feeding strip binding material to a position adjacent a stack, and a slidable member movable edgewise of the stack having means for clamping the stack engageable with the top thereof, said member also having a pair of pivoted fingers for bending the strip material about the stack while the latter is subjected to said clamping means.

HENRY GORA. 45
